UNITED STATES PATENT OFFICE.

EDWARD B. FIELD AND ATLEE F. HUNT, OF OAKLAND, CALIFORNIA.

CIGAR CUTTER.

Application filed July 26, 1920. Serial No. 398,996.

To all whom it may concern:

Be it known that we, EDWARD B. FIELD and ATLEE F. HUNT, citizens of the United States, residing at Oakland, in the county 5 of Alameda and State of California, have invented certain new and useful Improvements in Cigar Cutters, of which the following is a specification.

This invention relates to cigar cutters, and 10 has for its object to provide a mechanism which will open the end of a cigar without mutilating it.

Another object is to provide a cutter which is simple in construction and therefore 15 may be manufactured very inexpensively.

These objects are accomplished by the particular construction and arrangement of parts, shown in the accompanying drawing, 20 and in which:

Figure 1 is a side view of our improved cigar cutter.

Figure 2 is a view similar to Figure 1 but with the cutter telescoped.

Figure 3 is a section taken on the line 25 3-3 of Figure 1.

Figure 4 is an enlarged view similar to Figure 3 with a portion of the cutter broken away to show the cleaning pin.

Referring more particularly to the drawing, the numeral 1 indicates a cylindrical body, the upper portion of which is slightly enlarged to accommodate a conical recess 2, which is adapted to receive the end of the 35 cigar. A central bore 3 extends the length of the body 1 into the recess 2.

A cylindrical knife 4 reciprocates in the bore 3, and has a head 5 secured to the end thereof. A pin 6 secured in the lower portion 40 of the body 1 reciprocates in longitudinal slots 7 arranged diametrically opposite each other in the knife 4. A cleaning plunger 8 is secured within the knife 4 by the pin 6, one end of said pin extending to the inner end of recess 2. It will be seen 45 that the plunger 8 remains stationary while the knife 4 moves past it. The pin 6 also serves as a stop for the knife 4, in limiting its movement in both directions. The limit

of movement of the knife 4 is the length of 50 the slot 7.

A ring 9 is secured to the head 5, so that the cutter may be conveniently attached to a watch chain or a key ring.

The operation of our invention is as follows:

The knife 4 is withdrawn to the position shown in Figure 1, and the cigar end is inserted in the recess 2. The knife is now forced into the cigar to the position shown 60 in Figure 2, which cuts a round plug from the cigar and opens it. The cigar is now removed after which the knife 4 is withdrawn, the plunger 8 ejecting the plug of tobacco 65 from the knife.

Having described our invention, we claim:

1. A cigar cutter comprising a body having a central longitudinal bore and a conical recess in one end thereof, a tubular knife reciprocatively mounted in said bore, said 70 knife being provided with longitudinal slots arranged diametrically opposite each other, a stationary pin in said knife, one end of said pin extending to the inner end of said recess, a pin extending through the other end of 75 said pin and through said slots and secured in said body, the ends of said slots engaging said pin to limit the movement of said knife in both directions.

2. A cigar cutter comprising a body having a central longitudinal bore and a conical recess in one end thereof, a tubular knife reciprocatively mounted in said bore, said 80 knife being provided with longitudinal slots arranged diametrically opposite each other, 85 a stationary pin in said knife, one end of said pin extending to the inner end of said recess, a pin extending through the other end of said pin and through said slots and secured in said body, the ends of said slots engaging 90 said pin to limit the movement of said knife in both directions, a head on the outer end of said knife, and a ring connected to said head.

In testimony whereof we affix our signatures.

EDWARD B. FIELD.
ATLEE F. HUNT.
